(57) **CLAIM**

The ornamental design for a wall cabinet, as shown and described.

DESCRIPTION

FIG. 1 is a rear perspective view of a wall cabinet design showing my new design.

FIG. 2 is a front view of the wall cabinet.

FIG. 3 is a rear view of the wall cabinet.

FIG. 4 is a bottom view of the wall cabinet.

FIG. 5 is a top view of the wall cabinet.

FIG. 6 is a left view of the wall cabinet; and,

FIG. 7 is a right view of the wall cabinet.

Any shading is not a feature of the design but is utilized to illustrate the surface contours of the wall cabinet design in the drawings.

The broken lines in the figures show portions of the wall cabinet and form no part of the claimed design.
